I. E. PALMER,
HAMMOCK ATTACHMENT,
APPLICATION FILED JAN. 14, 1909.

921,623.

Patented May 11, 1909.

UNITED STATES PATENT OFFICE.

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

HAMMOCK ATTACHMENT.

No. 921,623.

Specification of Letters Patent.

Patented May 11, 1909.

Application filed January 14, 1909. Serial No. 472,192.

To all whom it may concern:

Be it known that I, ISAAC E. PALMER, a citizen of the United States, and a resident of Middletown, in the county of Middlesex and State of Connecticut, have invented an Improvement in Framed Hammocks, of which the following description, in connection with the accompanying drawings, is a specification, like numerals on the drawings representing like parts.

This invention relates to hammock attachments and is a division of my co-pending application, Serial No. 441,533.

In order that the principles of the invention may be clearly understood, I have illustrated an embodiment thereof in the accompanying drawings, wherein—

Figure 1 is a perspective view of a framed hammock having a rail or bar extending longitudinally thereof to serve as a back rest or guard or as a support for a curtain or wind shield; Fig. 2 is a detail representing a slightly modified means for supporting said curtain; Fig. 3 is a still further modification thereof; Fig. 4 is a perspective view representing the preferred manner of detachably securing the rail or bar to the hammock end; Fig. 5 is a side elevation of the preferred means for detachably securing the rail to its end members; Fig. 6 is a longitudinal, central, sectional elevation thereof upon the lines 6—6 of Fig. 5; and Fig. 7 is a view similar to Fig. 5, but representing means for supporting a plurality of rails.

Framed hammocks such as shown in my Patent No. 901,936 or of other types have been for some time upon the market, and while meeting with great favor have been found deficient in that no back rest has been provided for the user or users when sitting upright. Although certain types of framed hammocks are provided with flat frames adapted to support the user in a procumbent position, thereby in effect forming suspension couches, yet frequently such suspension couch is used merely as a seat for one or more persons. By providing a preferably detachable back rest or guard, it will be apparent that the suspension couch or a framed hammock of whatever type may be comfortably used by one or more persons sitting transversely of the hammock. My invention may also be applied to couches or other similar

structures not of the suspension type, to form a rest or guard.

Referring more particularly to the drawings, in Fig. 1 I have represented one form of my invention. Therein I have provided a rail or bar 6 adapted to be connected in any suitable manner with the end portions 2 and 2 of the hammock, but preferably in such a manner as to permit adjustment thereof. Herein I have represented said rail or bar as adjustable both vertically and transversely of the hammock. While any suitable means may be provided for the purpose, I have in Figs. 1 and 4 represented end members 7 preferably formed of wire having hooked ends 8 and 9 adapted to be received upon the end spreaders 3 of the hammock as indicated. Preferably, said wires 7 are provided with a vertical portion 10, whereto are secured for vertical adjustment thereon the brackets 11, also secured in any suitable manner to the rail 6 at its ends and provided with a plurality of spaced, similar partial bearings 12, between which is an opposite partial bearing 13. Received in an opening in said bearing 13 is a set screw 14. Said partial bearings 12 and 13 are adapted to embrace the vertical members 10 of the wires 7, whereon they may be adjusted at any suitable height.

As most clearly indicated in Fig. 4, the extreme ends of the hooks 8 are inwardly bent, as represented at 15, to prevent accidental displacement of the wires 7 from the hammock spreaders. The wires 7 may be readily positioned upon the hammock spreaders by holding said wires with the inclined portion thereof substantially normal to the end portions of the hammock to which they are to be attached. While so positioned, the hooks 8 may be slid downwardly into engagement with the end spreaders. Thereupon the inclined portions of the wires are swung into parallelism with the end portions of the hammock, as represented in Fig. 1, and the hooks 9 are then engaged with the end spreaders, as represented in Figs. 1 and 4. For this operation the said screws 14 should be slightly loosened to permit the swiveling action of the wires. The wires 7 may be positioned at any desired point laterally of the hammock by engaging them with the spreaders between the proper suspension of the cords 4 which thus serve as adjusting sup-

ports, whereby any suitable lateral adjustment may be effected. In use and when the rail 6 is subjected to strain, the hooks 9 or 8, as the case may be, are held from sliding by 5 engagement with the proper suspension cord.

4. Any other suitable means providing lateral adjustment may be employed.

It is apparent that any suitable number of bars or rails may be provided. In Fig. 7, I 10 have represented a pair of bars 16, 16, preferably suitably attached to a bracket similar to that represented in Fig. 5, but herein having spaced portions 17, 17, to which said rails are secured. Said rail or rails may be 15 of any suitable material and cross section, and if desired may be slightly bent outwardly from end to end to accommodate more readily the back of the user.

I may provide the rail or rails 6 with a curtain or shield 18 of any suitable material, as 20 indicated most clearly in Fig. 1. Preferably said curtain is so supported from the rail 6 as to be adjustable longitudinally thereof to suit the convenience of the user of the hammock. In Fig. 1, I have represented the curtain 18 as provided with a hem 19 wherein in the rail 6 is inserted. If desired, said curtain may be provided with a pocket 20.

In Fig. 2, I have represented a slightly 30 modified form of the invention wherein the curtain 18 is provided with rings 21 mounted upon the rail 6 to permit the ready longitudinal adjustment of the curtain. While said rail is in this figure represented as circular in 35 cross section, it is apparent that it and the rings may be rectangular in cross section or of any other suitable shape.

In Fig. 3, I have represented a slightly 40 modified form of means for attaching the curtain 18 to the rail 6. Herein, said rail is provided with hooks 22 and the curtain is provided with eyelets 23.

It will be apparent from the foregoing description that I have provided a framed 45 hammock suitable for use as a suspension couch or a seat of any desired type, with a back rest or shield. The rail or rails when used as a back rest support the user or users, when sitting transversely thereof, or as a 50 shield serves when the user occupies a pro-cumbent position to protect him from drafts or observation. The attachment is readily adjustable both vertically and 55 transversely of the hammock and hence to any desired height or position, and moreover being detachable may be conveniently shipped or stored.

Having thus described one illustrative embodiment of my invention, I desire it to be 60 understood that although specific terms are employed they are used in a generic and descriptive sense and not for purposes of limitation, the scope of the invention being set forth in the following claims.

65 1. As an article of manufacture, a rail for a

couch or the like, said couch having end portions with transverse members, and means for adjustably connecting said rail to said transverse members.

2. A framed hammock comprising, in combination, a body, a frame applied thereto and co-operating to form a seat or couch, said body having upright ends with transverse portions and spaced clue cords, and a rest or guard extending longitudinally of said hammock, supported by said transverse portions, and transversely adjustable with respect to 75 said clue cords.

3. A hammock or couch having upright 80 end portions, a bar extending longitudinally of the hammock, and means to connect said bar to said end portions with capacity for vertical and transverse adjustment.

4. As an article of manufacture, a rail for a couch or the like, said couch having end 85 portions with transverse members, said rail being provided at each end with spaced means for adjustably connecting the same with the transverse members of said couch.

5. A framed hammock or couch comprising, in combination, a body, a frame applied thereto, said body having upright ends having transverse portions, and a rest or guard extending longitudinally of said hammock or couch and provided at its ends with hooks to 95 be supported by said transverse portions.

6. As an article of manufacture a rail for a couch or the like, said couch having end portions with transverse members, said rail having spaced hooks pivotally connected to each 100 of its ends and adapted to be adjustably connected with said transverse members.

7. As an article of manufacture, a rail for a couch or the like, said couch having end portions with transverse members, and 105 means for adjustably connecting said rail to said transverse members, said rail having capacity for adjustment as to height.

8. A framed hammock comprising in combination a body, a frame applied thereto and co-operating to form a seat or couch, said body having upright ends provided with spreaders and spaced clue cords and a rest or guard extending longitudinally of said hammock, supported upon said spreaders and 110 transversely adjustable between said clue cords.

9. A framed hammock comprising in combination a body, a frame applied thereto and co-operating to form a seat or couch, said body having upright ends provided with spreaders and spaced clue cords and a rail 120 extending longitudinally of said hammock and provided with hooked ends supported by said spreaders and adjustable between the 125 clue cords.

10. A framed hammock comprising in combination a body, a frame applied thereto and co-operating to form a seat or couch, said body having upright ends provided with 130

spreaders and spaced clue cords, and a rail extending longitudinally of the hammock, supported by said spreaders, and adjustable transversely with respect to said clue cords and vertically with respect to said frame.

11. A framed hammock comprising in combination a body, a frame applied thereto and coöperating to form a seat or couch, said body having upright ends provided with suspension means and a rail extending longitudinally of the hammock and provided with re-

movable hooked ends adapted to engage said upright ends, said rail being adjustably supported by said suspension means.

In testimony whereof, I have signed my 15 name to this specification, in the presence of two subscribing witnesses.

ISAAC E. PALMER.
